UNITED STATES PATENT OFFICE.

ALBERT M. PRICE, OF CHICAGO, ILLINOIS, ASSIGNOR TO WILLIAM H. FAUBER, OF SAME PLACE.

DESIGN FOR A CRANK-ARM FOR VELOCIPEDES.

SPECIFICATION forming part of Design No. 32,348, dated March 13, 1900.

Application filed February 12, 1900. Serial No. 5,029. Term of patent 7 years.

To all whom it may concern:

Be it known that I, ALBERT M. PRICE, a citizen of the United States, residing at Chicago, in the county of Cook and State of Illinois, have invented and produced a new and original Design for a Crank-Arm for Velocipedes, of which the following is a specification, reference being had to the accompanying drawings, forming part hereof.

10 In the drawings, Figure 1 is a side elevation of a crank-arm embodying my design. Fig. 2 is a rear elevation thereof.

The leading or characteristic features of a crank-arm made in accordance with my design are as follows: The crank-arm is made smaller at its outer than at its inner end, where it joins the crank-shaft, is rectangular in cross-section at a point closely adjacent to the head thereof, to which the pedal-shaft is attached, and of lozenge or diamond shape in cross-section at its inner end or adjacent to the crank-shaft. At said outer end of the arm the four plane faces thereof form the front, rear, and side surfaces of the arm, and said plane faces taper gradually toward the inner end of the arm, where the two margins of each of said surfaces are brought together, or nearly so. The four oblique faces forming the diamond or lozenge shaped inner end of 30 the arm are similarly tapered from the inner

toward the outer end thereof and meet or intersect the said tapered front, rear, and side faces thereof. It follows that the margins of each said oblique surfaces are coincident with the margins of the front and side or rear and side surfaces on each side thereof, so that said oblique surfaces are widest at the inner end of the arm and taper toward the outer end thereof, where their margins intersect each other, and at the meeting edges of the four plane surfaces, which give the rectangular form to the arm at that point.

At the intersection of the arm and shaft, at the outer side thereof, the parts are convexly rounded, such rounded surface being a continuation of the cylindric surface of the shaft. Said convexly-rounded surface is intersected by the two outside oblique surfaces. The inner oblique surfaces of the arm extend to the cylindric surfaces of the shaft and are merged 45 into said cylindric surface.

I claim as my invention—

The design for a crank-arm for velocipedes, substantially as herein shown and described. Signed at Chicago, Cook county, Illinois, on 55 this 3d day of January, 1900.

ALBERT M. PRICE.

In presence of—

C. W. HILLS,
GERTRUDE BRYCE.
